E. L. ANDERSON.
COMBINED MATCH CASE AND CIGAR CUTTER.
APPLICATION FILED FEB. 13, 1915.

1,156,513.

Patented Oct. 12, 1915.

UNITED STATES PATENT OFFICE.

EDWARD L. ANDERSON, OF ATTLEBORO, MASSACHUSETTS, ASSIGNOR TO R AND G COMPANY, OF ATTLEBORO, MASSACHUSETTS.

COMBINED MATCH-CASE AND CIGAR-CUTTER.

1,156,513.

Specification of Letters Patent.

Patented Oct. 12, 1915.

Application filed February 13, 1915. Serial No. 7,948.

To all whom it may concern:

Be it known that I, EDWARD L. ANDERSON, a citizen of the United States, residing at Attleboro, in the county of Bristol and State of Massachusetts, have invented a new and useful Improvement in Combined Match-Cases and Cigar-Cutters, of which the following is a specification.

This invention relates to certain new and useful improvements in combined match cases and cigar cutters, and the primary object thereof is to provide a case which removably retains a package of matches and which also movably supports a cigar cutter so that upon opening of the case the cutter may be moved to a position to enable cutting of the cigar, and then returned to a position within the case.

A further object of the invention is to provide improved means for retaining the match package so that upon exhaust of the matches a new or fresh package may be inserted in the case; to provide an improved form of cutter and manner of mounting same movably within the case, and to otherwise generally provide a neat, simple, compact and inexpensive case of the character indicated.

In the drawings Figure 1 is a perspective view of the case closed. Fig. 2 is a plan view of the case open. Fig. 3 is a central longitudinal section view of Fig. 2. Fig. 4 is a section on the line 4—4 of Fig. 2, and Fig. 5 is a detail perspective view of the cutter blade.

The case is formed of two parts 1 and 2, the latter having fingers 3 which extend inwardly toward each other and which engage a package of paper or wood matches M, the package being insertible beneath the fingers and withdrawable from therebeneath for purpose of renewal or replacement.

The cigar cutter comprises a hollow casting 4 formed with the usual cigar tip receiving opening 5, and has on its interior a pair of shoulders 6 adapted to engage fingers or projections 7 formed on the free ends of the flexible or compressible spring legs 8 of the cutter blade 9. By this structure the cutter blade can be completely finished and

sharpened, and its legs compressed and forced into the interior of the casing 4, and upon passing the shoulders 6, the legs will expand and by engagement of the shoulders with the projections 7 of the cutter blade 55 legs, the outward movement of the cutter blade will be limited as is obvious.

The cutter is hinged within the part 1 by means of a connection comprising a leaf spring 10 having right angular ends 11 to 60 which the housing 4 is pivoted by means of pins 13. The leaf spring is corrugated so as to provide resilient abutments 14 that engage the hinged end of the cutter housing to thereby hold the cutter housing in both 65 open and closed positions *i. e.*, the position shown in Fig. 3, and that shown in Figs. 2 and 4. The leaf spring has an arm 15 which is rigidly connected to the part 1, so as to movably support the spring part that has 70 the corrugations for movement toward and away from the part 1. The cutter structure is thus held in both of its two positions and is prevented from rattling in the part 1 when the case is carried in the pocket. 75

Having thus described my invention, what I claim as new and desire to secure by Letters Patent is;

1. A case composed of two hinged parts, means borne by one of the parts to releasably engage and retain a package of matches therein, a cigar cutter hinged to the other part, and spring means to engage the cutter to hold same against said other part or in position out of engagement with said other 85 part.

2. A case composed of two hinged parts, a leaf spring having corrugations and right angular ends movably connected to one of the parts, and a cigar cutter pivoted to said 90 spring ends and engaged with said corrugations.

In testimony whereof I have signed my name to this specification in the presence of two subscribing witnesses.

EDWARD L. ANDERSON.
